CLAIM

The ornamental design for an x-ray fluorescence spectrometer as shown and described.

DESCRIPTION

FIG. 1 is a perspective view of an x-ray fluorescence spectrometer.

FIG. 2 is a front view thereof.

FIG. 3 is a rear view thereof.

FIG. 4 is a top view thereof.

FIG. 5 is a bottom view thereof.

FIG. 6 is a left side view thereof.

FIG. 7 is a right side view thereof; and,

FIG. 8 is a partially enlarged view from the perspective of 8-8 in FIG. 1.

The broken lines in the drawings are included for the purpose of illustrating environmental structure and form no part of the claimed design.
